(57) **CLAIM**

The ornamental design for a ventilating and heating assembly, as shown and described.

DESCRIPTION

FIG. 1 is a perspective view of a ventilating and heating apparatus according to an exemplary embodiment of the present invention;

FIG. 2 is an end view of the apparatus shown in FIG. 1; FIG. 3 is an opposite end view of the apparatus shown in FIG. 2;

FIG. 4 is a top view of the apparatus shown in FIG. 1; FIG. 5 is a bottom view of the apparatus shown in FIG. 1; FIG. 6 is a side view of the apparatus shown in FIG. 1; and, FIG. 7 is an opposite side view of the apparatus shown in FIG. 6.

The broken line showing of the environment is for illustrative purposes only and forms no part of the claimed design. The broken lines which define the boundaries of the claimed design form no part thereof.
